UNITED STATES PATENT OFFICE.

FRANK F. BURFITT, OF PORTLAND, OREGON.

SINK FIXTURE.

Application filed May 17, 1926. Serial No. 109,739.

One of the primary objects of my device consists in the construction of a device of this character having a finish and appearance similar to that of the finish placed upon the 5 sinks and sink backs.

Another object of my device consists in the construction of a device wherein all of the parts are hidden within the frame of the structure excepting the valve stems and the operating levers to be placed thereupon.

Still further objects of my device consists in so constructing the device that the metal parts of the same may be so made that no highly polished metal parts are required in 15 the construction of the same.

Still further objects of my device consist in providing a fixture that may be easily attached to the piping that has been placed in the roughing in process that is done by the 20 plumbers without the necessity of undue care being exercised in the placing of the piping and yet permit of the placing of the fixtures in position and alignment that is required of such devices.

Still further objects of my device consist in the construction of a device that may be easily adjusted and one wherein connection may be made with the least delay and wherein in the lidded closure of the main frame consists in a soap container that may be easily 30 removed and replaced thereupon.

With these and incidental objects in view, the invention consists in certain novel features of construction and combination of 35 parts, the essential elements of which are set forth in the appended claims, and a preferred form of embodiment of which is hereinafter shown with reference to the drawings which accompany and form a part of this specification.

In the drawings:—

Fig. 1 is a top plan view of the assembled device, shown in place upon a sink of the ordinary type.

Fig. 2 is an enlarged front elevation of the assembled device.

Fig. 3 is an enlarged sectional view, taken on line 3—3 of Fig. 4, looking in the direction indicated.

Fig. 4 is a top plan view partially in section.

Fig. 5 is a rear view, taken on line 5—5 of Fig. 4.

Fig. 6 is a side elevation of the mechanism shown in Fig. 2.

Like reference characters refer to like parts throughout the several views.

1 is a sink of the ordinary type and 2 is the sink back. In devices of this kind, the same is adapted for use in connection with 60 sinks and sink backs, wherein the same are porcelain covered and it is the object of my device to furnish a finish similar to that of the finish placed upon the sinks; the same may be made of burned clay with a glazed 65

surface, or made of china, or porcelain. The same consists primarily of a frame 3, having a rear wall 4, and a front wall 5, and having disposed equi-distant from the center line thereof, two cylindrical members 6 and 7 70 for the placing of valves 8 and 9 therein. I have here shown these valves as having valve stems disposed in the front end thereof, but I do not wish to be limited to valves having the operating handles disposed upon the 75 front as the same may be equally advantageously placed at either side or upon the top side of the same. Pipe connections 10 and 11 are placed in position during the roughing in process of the plumbers and are placed 80 substantially in position and alignment, but it is impractical to place the same in exact position and it therefore becomes necessary to provide compensation within reasonable limits to connect up the faucet fixtures with 85 this piping. To accomplish this result, I place a fitting 12 central of the frame 3, having gland nuts 13 and 14 secured thereto, 90

into which short nipples 15 and 16 are made to engage and in slidable relationship therewith. These nipples are securely threaded into the valves 8 and 9 and when the connection has been made between the valve 9 and the pipe 10, and the valve 8 and the pipe 11, the compensation for unevenness in alignment in position is made by the slidable 95 relation existing between the nipples and the gland nuts; after the same have been properly positioned, the gland nuts are then tightened. Slots 17 and 18 are provided through the rear walls of the cylindrical members, through which the pipes 10 and 11 are made to pass, to further compensate for any unevenness in location and placement of the pipes 10 and 11. Operating levers are 100

placed on the valve stem of valves 8 and 9 to facilitate the movement and opening and closing of the valves. An adjustable outlet pipe 19 is provided adapted to be swung to either side about its pivotal center and is 110

secured to the fitting 12 by a gland nut and in swivel relationship therewith. A band 20 is loosely mounted about member 19 and in 5 slideable relationship with the frame 3 to give finish and appearance to the fixture. A removable soap container 21 is disposed upon the upper surface of the frame 3, and is adapted to be removed therefrom, the same being maintained in position by a suitable 10 fastening means, as a screw member 22, that is threaded into the boss 23 of the fitting 12. An outlet spout 24 is disposed from the soap container and is adapted to deliver liquid being deposited therein at the rear side thereof. Removable members 25 and 26 are disposed about the inner portion of the valve 15 stems of the valves 8 and 9 and are preferably made of the same material as that of the frame 3, to give finish and appearance 20 to the entire covering. The removal of the soap container 21 from the frame 3, permits of the adjustment of the fitting 12 and the nipples 15 and 16 therewith and in effect opens the entire upper surface of the frame 3 25 to facilitate inspection and adjustment; the placing of the same in position in effect closes the opening, thus created by its removal and gives a finished appearance to the entire device.

30 While the form of mechanism herein shown and described is admirably adapted

to fulfill the objects primarily stated, it is to be understood that it is not intended to confine the invention to the one form of embodiment herein shown and described, as it is 35 susceptible of embodiment in various forms, all coming within the scope of the claims which follow.

What I claim is:—

1. A sink fixture comprising a frame made 40 from plastic material, a fitting within and disposed centrally of said frame, a valve disposed in said frame at each side of said fitting, nipples connecting the valves and fitting, gland nuts connecting the nipples with 45 the fitting, and a soap container removably connected to said frame and adapted to form a closure to the frame.

2. A sink fixture comprising a frame, a fitting within said frame and disposed central 50 thereof; a valve within said frame at each side of said fitting; nipples slidably connecting said valves to said fitting; gland nuts connecting the fitting and the nipples; 55 slots formed through the rear wall of said frame in alignment with the inlets of said valves for the insertion of exterior connections for said valves; an outlet pipe swivelly connected to said fitting; and a band loosely disposed between the outlet pipe and said 60 frame.

FRANK F. BURFITT.
